(57) **CLAIM**

The ornamental design for an ingot, as shown and described.

DESCRIPTION

1.-6. Ingots

1.1 illustrates a side view of an ingot according to the invention;

1.2 illustrates a top view of the ingot according to 1.1;

1.3 illustrates a bottom view of the ingot according to 1.2 under ultraviolet light;

1.4 illustrates a bottom view of the ingot according to 1.2. Broken lines shown in the drawings represent unclaimed portions of the ingot and form no part of the claimed design.
